UNITED STATES PATENT OFFICE.

CHARLES H. SAMPSON, OF ROCHESTER, NEW YORK, ASSIGNOR TO PEERLESS CHECK PROTECTING COMPANY, OF ROCHESTER, NEW YORK, A CORPORATION OF NEW YORK.

PRINTING-DIE.

1,135,053.

Specification of Letters Patent. Patented Apr. 13, 1915.

Application filed April 18, 1913. Serial No. 761,886.

To all whom it may concern:

Be it known that I, CHARLES H. SAMPSON, of Rochester, in the county of Monroe and State of New York, have invented a new and 5 useful Improvement in Printing-Dies, which improvement is fully set forth in the following specification and shown in the accompanying drawings.

The present invention relates to printing dies and more particularly to that type in which the dies, in addition to printing, rupture or break the paper in order that an erasure of the printed matter can not be effected, such dies being generally used on what 10 is known as check protectors or check writing machines, such, for instance, as machines of the type shown in Patent #1,010,180 granted to me the 28th day of November, 1911; and an object of this invention is to provide a construction in which the dies are so formed that the printing surface maintains a flat face for the reception 15 of the ink and thus gives a perfect impression even after the machine has been used a great length of time.

To these and other ends the invention consists in certain parts and combinations of parts all of which will be hereinafter described, the novel features being pointed out 20 in the appended claims.

In the drawings: Figure 1 is a side elevation, partly in section, of a machine constructed exactly like that shown in my Patent #1,010,180 with the exception that the 25 improved dies, forming the subject matter of this invention, are employed; Fig. 2 is an enlarged sectional view in the direction of the printing line through both of the dies; Fig. 3 is an enlarged plan view of the character die; Fig. 4 is an enlarged plan view of the platen die; and Fig. 5 is an enlarged view of a character printed by the printing dies.

In my patent before mentioned, there is 30 employed a base frame 1 having a casing 2 pivotally mounted thereon at 3. The base frame 1 carries a platen die 4 and the casing 2 is provided with a printing wheel or member 5 turning about the axis 6 and having 35 character dies on its periphery. An inking roller 8 is carried by an oscillating casing 9 which turns about the axis 6 and is shifted with each printing operation to and from

printing position by a mechanism shown more fully in the before-mentioned patent. 55

The present invention has to do with the printing dies for a machine of this type or other constructions wherein the same objects or results are desirable.

The printing die is formed from soft 60 metal with each character 10 projecting from the face of the holder or wheel 5. The face of each character is formed with grooves 11 preferably of V-shape in cross section and extending from one side of the 65 type to the other, in this instance, from the top to the bottom, and at an oblique angle to the height of the character, the depths of these grooves being not so great as the depths of the characters. The faces 12 of 70 the characters between the grooves 11 are flat in order to provide a surface for retaining the ink and the purpose of this invention is to maintain these inking surfaces in a flattened condition and cause them to be pressed 75 firmly against the paper notwithstanding that the machine has been used a great length of time.

The platen die 4 is provided, from one end to the other, with projections 13 extending transversely of said platen die in parallel relation, having V-shaped cross sections and lying at angles corresponding to the oblique angles of the grooves in the printing characters. These projections correspond in 80 width and height to the notches or grooves in the printing characters and are adapted to be received within such grooves to entirely fill the latter, forming with the same the means which ruptures or cuts the paper. 85 Between the projections 13, the platen die is formed with flattened faces 14 which correspond in width to the width between the grooves or notches of the character die, so that the printing faces 12 of the characters 90 will have a surface against which it may abut to firmly press the ink upon the paper.

From the foregoing it will be apparent 95 that the character die and the printing die are so formed that one matches the other, that is, the printing die characters and the platen die have projecting surfaces and recesses which intermesh in such a manner 100 that the paper is broken or ruptured while the ink is firmly pressed or squeezed against 105 the paper, said ink passing through the rup-

tured portion and giving a clear character which cannot be obliterated.

What I claim as my invention and desire to secure by Letters Patent is:

5. 1. The combination with a character die formed with projecting printing characters having flat ink-receiving faces and grooves, of a platen die having rupturing projections entering said grooves and entirely filling 10 the same in order to force the ink into the ruptured edges of the paper and also having flattened portions coöperating with flattened ink-receiving faces on the character die.
  15. 2. The combination with a platen die formed with projecting printing characters having flattened ink-receiving faces and parallel grooves extending from one side of each character to the other, of a platen die having flattened faces for coöperation with 20 the flattened faces of the character die and also having parallel rupturing projections adapted to be received within and to entirely fill the grooves of the character die in order to force the ink into the ruptured 25 edges of the paper.
  3. The combination with a printing member having a plurality of character dies thereon, each character die having its characters formed with flat ink receiving faces 30 and with grooves extending from one side of
- the character to the other between the flat ink receiving faces and at an oblique angle to the height of the character, of inking mechanism for the character dies, and a platen die having transversely extending 35 projections adapted to be received within, and to fill entirely, the grooves of the characters and having also flattened faces between the projections to coöperate with the flattened faces on the character dies. 40
4. The combination with a printing member having a character projecting from the face thereof and formed with parallel V-shaped grooves extending from one edge of the character to another and flat ink receiving faces between said grooves, of a platen die having parallel projections with V-shaped cross sections arranged to be received within said grooves and entirely fill the same in order to force the ink into the 45 ruptured edges of the paper and having flattened faces between the projections for coöperating with the flattened faces of the character, and inking means for inking the characters. 50
